UNITED STATES PATENT OFFICE.

EPHRAIM SMITH, OF PITTSBURG, PENNSYLVANIA, ASSIGNOR TO GEORGE V. WILLSON, OF SAME PLACE.

MOWING-MACHINE.

SPECIFICATION forming part of Letters Patent No. 445,347, dated January 27, 1891.

Application filed January 27, 1886. Serial No. 189,888. (No model.)

To all whom it may concern:

Be it known that I, EPHRAIM SMITH, of Pittsburgh, Allegheny county, State of Pennsylvania, have invented certain new and useful Improvements in Mowing-Machines, of which the following is a true and exact description, reference being had to the accompanying drawings, which form a part of this specification.

10 The object of my invention is to provide a simple and effective means of floating during use the finger-bar of a mowing-machine, the arrangement of parts being such that both ends of the finger-bar are balanced at the same time, so as to readily follow the inequalities of the ground, by means of an adjustable spring connection extending obliquely downward from the machine-frame to a standard located upon the finger-bar in proximity to the point of connection of the latter with the coupling-bar.

15 In the accompanying drawings illustrative of my invention, Figure 1 represents in rear elevation a rear-cut mowing-machine provided with one form of my improvement. Fig. 2 represents in detail perspective and on a larger scale a separate view of the parts constituting said form; and Fig. 3 represents an alternative form of spring connection, 20 which may be substituted for that shown in the other figures.

Similar letters of reference indicate similar parts throughout the several views.

25 In the mowing-machine shown in the drawings, A indicates the frame; B B, the wheels; C, the finger-bar; D, the coupling-bar hinged thereto at E; G, the drag-bar, and J the ordinary lifting or gagging lever.

30 Upon a suitable bearing upon the machine-frame is mounted the sprocket wheel or pulley K, and over the teeth of this wheel extends the connection I, extending obliquely downward and being attached to an upright standard F, secured upon or attached to the 35 finger-bar at its inner shoe and in proximity to its point of connection with the coupling-bar. As part of the connection I in the form of my invention shown in Figs. 1 and 2 is the spring H, which, as is obvious, may be adjusted 40 by catching its hooked end i into different links of the sprocket-chain.

In the form of my invention shown in Fig. 3 I substitute for the spring H a coiled spring k, located within the sprocket-wheel itself, and connected, for instance, at one end to the 55 interior surface of said wheel and at the other end to the rigid axis, upon which it turns.

The operation of my improvement is easily followed upon the drawings. The upright standard F should be placed close to the hinge E, so as to be out of the way of the grass, and its height must be such that the action of the spring pulling obliquely upward from its upper end will tend at the same time to lift both the inner and outer shoes of the finger-bar. Its height of course will vary with the length of the finger-bar and the position of the upright standard with respect to the hinge of the finger-bar. I prefer in all cases to attach the connection I to the frame of the machine in such a way that it can be continued past the point of suspension and connected with the lifting-lever J, so that the driver can by the same connection easily lift the finger-bar to pass an obstruction or throw it up 75 out of operative position. It is important, however, that the adjustment of the spring to sustain the finger-bar in operation should be entirely independent of this lever. I conveniently secure this result in the construction shown in Fig. 3, inasmuch as by adjusting the chain upon the teeth of the sprocket-wheel the resiliency of the coiled spring therein may be varied at will, so that any desired amount of lifting force can be applied to the 85 end of the upright standard F. Additional advantages result from the employment of this construction. Thus the spring, being inclosed, is protected, and moreover it not only serves to balance or float the finger-bar when 90 it is in operation, but also aids the driver in lifting or gagging the same by means of the lever.

To effect the union of the spring-sustaining device and the lifting-lever in the most useful way, the height of the upright standard F should be gaged so as to act with more power upon the outer end of the finger-bar than upon its inner end. This is necessary not only because it places the outer end of the 100 finger-bar more directly under the control of the driver, but also because it is more impor-

tant to keep the weight of the finger-bar off the ground at its outer end than at its inner end.

Having thus described my invention, what I claim, and desire to secure by Letters Patent, is—

In a mowing-machine, the combination, with the coupling-bar, of a finger-bar pivotally connected therewith, a standard located upon the finger-bar near the point of connection of the finger-bar and coupling-bar, a lifting-lever, and an adjustable spring connection between

15 said lever and the finger-bar, attached at one end to the lever, extending thence over a point on the frame above and inward of the finger-bar's pivot to the standard on said finger-bar, substantially as and for the purposes set forth.

EPHRAIM SMITH.
